PHOTOGRAPHIC REPRODUCTION APPARATUS

Application filed May 10, 1930, Serial No. 451,386, and in Switzerland May 18, 1929.

This invention relates to apparatus for the production of photographic duplicates by means of a photo-luminous element.

Nowadays photo-luminous elements are frequently used for photographic reproduction, i. e. papers, cards, plates etc., which have the property after treatment with a photo-luminous substance, of storing up light upon being illuminated and of emitting the same or phosphorescing in the dark. If such a photo-luminous element, often called "Luminophor" for short, after having been exposed to light, is brought together with the object to be reproduced, for example written matter, on a plate provided with a light-sensitive layer and placed in the dark, the exact latent reproduction of the original is obtained by means of the light-giving "Luminophor" and has only to be developed in the usual manner. This method of reproduction is known, but there is not in existence a practical apparatus which can be readily operated by anyone, for effecting this procedure.

According to the present invention apparatus for the production of photographic duplicates of written, drawn, or printed matter or the like, by means of a photo-luminous element is provided to meet the need hereinbefore referred to, this apparatus having one frame-part arranged to contain a source of light and another frame-part arranged to receive the original to be reproduced together with a light sensitive material for receiving the reproduction, in combination with a carrier for receiving a photo-luminous element, means being provided for allowing a relative movement between the photo-luminous element carrier and the frame-part carrying the original to be reproduced and the light sensitive material, in such a manner that after illumination of the photo-luminous element, the latter can be moved so as to act through the original on the light sensitive material.

The accompanying drawings show by way of example only an embodiment of the invention, in the form of a box adapted to be opened on a hinge, Figures 1 and 2, being vertical sections of the apparatus while in

use, and Figure 3 a plan view of the same with the "Luminophor" carrier removed. Figure 4 shows the box closed and containing the "Luminophor" carrier, which is shown in section in Figure 5.

The apparatus illustrated in the drawings is in the form a box adapted to be opened on a hinge and consisting of a lower part B and an upper part C. The parts B and C of the box are of equal height so that when the box is open the upper surfaces of the parts B and C lie in one plane and their lower surfaces in another plane.

The apparatus still comprises the "Luminophor" carrier A which when not in use is kept in the lower part B of the box (Figure 4), and when the box is opened may be placed for use on the part C and rolled from the latter over the part B and back.

The "Luminophor" carrier A has a frame a, which has a recess for receiving a slide c accommodating the "Luminophor" b. The frame a is provided at one side with a roller d, of rubber for example. Furthermore, there are provided on the opposite side of the frame a two rolling balls e, which facilitate to and fro sliding movement of the "Luminophor" bearing frame over the two parts B, C, of the box. For protecting the "Luminophor" b against the injurious effects of the atmosphere, a glass plate f is provided in the frame a, which is rendered air tight by means of felt. For stability, the "Luminophor" carrier is loaded by a weight g, which may consist of a plate of iron, lead, etc.

When the box is open the lower part B is arranged to receive an original h to be reproduced, this being placed over the light sensitive paper i. The lower part B of the box is provided with a groove j and with two recesses j¹ for receiving respectively roller d and rolling balls e of the "Luminophor" carrier, so that the latter comes to rest in the groove j and the recesses j¹ when the "Luminophor" carrier A is rolled over the part B of the box, and is thus maintained in position on the part B.

In the part C of the box several electric illuminating devices k are located which are

connected in a suitable manner to a lighting circuit by means of plugs and sockets.

The electric circuit of said illuminating devices, which includes the contact members *l* and contact springs *m* contains a contact device *n* (Figure 5), the movable member of which is controlled by a controlling pin *o*, which projects through the cover plate *C*¹ of the part *C* of the box. The cover plate *C*¹ 10 contains a matt glass plate *C*² and has a groove *p* and recesses *p*¹ corresponding to those *j*, *j*¹ of the lower part *B* of the box, which also serve for determining position of the "Luminophor" carrier *A* on the box part *C*.

When a reproduction is to be made, the apparatus is opened in a dark room, the "Luminophor" carrier *A* is placed in the position shown in Figure 1 on the part *C* of the box, and the apparatus is connected to a lighting circuit. As the sliding roller *d* in this position of the carrier *A*, presses down the controlling pin *o*, the contact device *n* is closed and current passes through the illuminating devices *k*. The light thus radiated is stored in the "Luminophor" *b* in the carrier *A*. In the meantime, the original to be reproduced has been placed on top of a light sensitive paper on the part *B* of the box. Now the "Luminophor" carrier *A* is rolled over the part *B* of the box. Thereby the lighting circuit is automatically opened at the contact device *n* owing to the release of the pin *o*. Then the "Luminophor" *b* 35 acts as source of light for the light sensitive paper *i* in order to produce a latent picture thereon. When the original or the light sensitive paper is sufficiently exposed, the "Luminophor" carrier *A* is rolled back over the part *C* of the box for the purpose of further 40 charging the "Luminophor" *b* with radiant energy whilst the paper *i* is removed and the latent picture developed. The hereinbefore described procedure may then be repeated 45 indefinitely.

It will be evident that these and other modifications may be made in the invention which is not limited to the particular construction and arrangement of parts hereinbefore described which may be varied as desired to suit particular requirements without exceeding the scope of the invention.

What I claim is:

1. An apparatus for the production of photographic duplicates of written, drawn, or printed matter or the like, by means of a photo-luminous element, comprising two frame-parts, the one arranged to contain a source of light and the other arranged to receive the original to be reproduced together with a light-sensitive material for receiving the reproduction, in combination with a carrier for receiving a photo-luminous element and guiding means to allow relative movement between the photo-luminous element

carrier and the frame-parts carrying respectively the source of light and the original.

2. An apparatus for the production of photographic duplicates of written, drawn, or printed matter or the like, by means of a photo-luminous element, comprising two frame-parts, hinged together like parts of a box, the one arranged to contain a source of light and the other arranged to receive the original to be reproduced together with a light-sensitive material for receiving the reproduction, in combination with a carrier for receiving a photo-luminous element, said frame-parts, when being in open position, being arranged to constitute a rolling surface for the photo-luminous element carrier, so as to allow same to be shifted from one frame-part to the other.

3. An apparatus for the production of photographic duplicates of written, drawn, or printed matter or the like, by means of a photo-luminous element, comprising two frame-parts, one arranged to contain a source of electric light and the other arranged to receive the original to be reproduced together with a light sensitive material for receiving the reproduction, in combination with a carrier for receiving a photo-luminous element, guiding means to allow relative movement of the photo-luminous element carrier with respect to the frame-parts carrying respectively the source of light and the original and electric contact means in the circuit of said electric light source for controlling same in dependence of the movement of said photo-luminous element carrier.

In witness whereof I have hereunto signed my name this 30th day of April, 1930.

MANO ZIFFER von TESCHENBRUCK.
